UNITED STATES PATENT OFFICE.

JACOB HUSS, OF MENDOTA, ILLINOIS.

HEEL GUARD AND THE LIKE.

Application filed October 1, 1925. Serial No. 59,792.

This invention has to do with improvements in heel guards for shoes. The invention has to do with an improved heel guard which may be easily attached to and removed from the heel.

The heel guard of the present invention may be used in connection with either leather or wooden heels, or rubber heels, but it is intended primarily for use in connection with rubber heels.

It is well known that rubber heels greatly increase the difficulty of putting on and removing rubbers and overshoes. This is because of the fact that the heel portion of the shoe is the last portion to be forced down into the overshoe, and, conversely, is the first portion to be withdrawn therefrom. The friction between the rubber and inside of the overshoe is so great that it is often practically impossible to put on the overshoe if it is a tight fit, and, in any case, the overshoe can only be put on by exercising considerable care in forcing the toe portion of the shoe well forward into the overshoe.

By the use of the heel guard of the present invention, I establish a temporary metallic lining beneath and around the rubber heel, the outside surface of said lining being polished so as to slide readily into and out of the overshoe. In this way, the rubber heel is very easily forced into place and will slide down into or up out of the overshoe without having to exercise extreme care in forcing the toe portion of the shoe forward to the extreme position.

The heel guard of the present invention is also so formed that it can be instantly attached to or detached from the heel; and so that it will firmly hold its place on the heel when in service. It is also so formed that it can be readily made from sheet metal stamping at very low cost.

Other objects and uses of the invention will appear from a detailed description of the same, which consists in the features of construction and combinations of parts hereinafter described and claimed.

In the drawing:

Figure 1 shows a side view of a shoe having applied to the heel thereof a guard embodying the features of the present invention;

Fig. 2 shows a plan view of the heel guard itself;

Fig. 3 is a front edge view on line 3—3

of Fig. 2, looking in the direction of the arrows; and

Fig. 4 is a side view on the line 4—4 of Fig. 2, looking in the direction of the arrows.

60

The heel guard itself comprises a crescent shaped sheetmetal stamping 5 which conforms to the shape of the rear portion of the heel with a fair degree of accuracy. This guard 5 has a floor 6 and encircling flange 65 7 around its side and rear portions. Preferably, the flange 7 is provided with a slight cant inwards, so that the upper edges of its side portions 8 and 9 are slightly closer together than the width of the bottom portion. As a result, the side flange will take a more secure hold on the side portions of the heel and be retained firmly in position thereon.

The extreme front ends of the side portions 8 and 9 of the flange are preferably flared outwards very slightly, as clearly indicated in Fig. 2, so as to avoid any tendency of these edges to bite into the sides of the heel during application thereto.

75

It is preferred that there be provided a forwardly reaching pointed pin 10 on the upper portion of the back of the side wall 7, so that as the guard is pressed forwards into final position on the heel, this pin will 85 stick into the upper solid portion of the heel and thus retain the guard more firmly in place thereon.

It is to be observed that the floor portion 6 should reach inwardly with respect to 90 the encircling flange 7 a sufficient distance to give a good contact around the edge portion of the bottom of the rubber heel. By so doing, the guard will retain its position more securely on the heel and insure more 95 perfect alignment thereon.

It is preferred that the floor 6 be carried forward in one rear corner a sufficient distance to insure complete protection beneath all of the outside corner of the rubber heel, 100 which ordinarily wears away most rapidly. For this purpose, the enlargement 11 is illustrated in Fig. 2. By this means there is assurance that when the guard is set into place on the rubber heel, the floor of the 105 guard will supplement the bottom of the rubber heel and straighten out the same so as to present a flat surface to the bottom of the overshoe when the same is set into place. In this way, a firm and normal pressure on 110

the bottom of the heel portion of the overshoe is insured not withstanding any amount of wear which may be present on the rubber heel itself. This will eliminate the tendency 5 of the heel portion of the overshoe to become broken down at the outer corner due to the irregular form of the rubber heel itself.

It will be understood that the heel guard 10 itself is preferably made of relatively thin metal stamping, so that when in place on the heel, it does not materially increase the size of the heel nor lower the bottom thereof.

15 While I have herein shown and described only a single embodiment of the features of my present invention, still I do not intend to limit myself to the same, except as I may do so in the claims.

20 I claim:

1. As a new article of manufacture, a heel guard for the purpose specified comprising a crescent shaped plate of sheet metal of proper size and contour to correspond 25 to the heel to which it is to be applied, and having an encircling flange around its outer edge, the upper portion of said flange being slightly canted inwards and the front edges of said flange being slightly 30 flared outwards, there being a relatively sharp pin projecting forward from the upper rear portion of the flange, the floor of

the crescent shaped plate being enlarged across one side of the rear portion thereof corresponding to the outer corner of the 35 heel to which the article is to be applied, substantially as described.

2. As a new article of manufacture, a heel guard for rubber heels comprising an exteriorly heel shaped base plate of metal 40 of substantially crescent shape formation and proper size and contour to fit smoothly against the marginal portion of the base of a rubber heel and being smooth and plane on its under side and having a flange upwardly extending from the exterior margin of its side and rear edges, the upper portion of the flange being slightly canted inwardly to impinge against and clamp upon the sides and back of a rubber heel. 45

3. As a new article of manufacture, a heel guard for rubber heels comprising an exteriorly heel shaped base plate of metal of substantially crescent shape formation and proper size and contour to fit smoothly 55 against the marginal portion of the base of a rubber heel and being smooth and plane on its under side and having a flange upwardly extending from the exterior margin of its side and rear edges, the upper portion of the flange being configured to impinge against and clamp upon the sides and 60 back of a rubber heel.

JACOB HUSS.
